UNITED STATES PATENT OFFICE

EDWARDS F. SCHERMERHORN, OF BROOKLYN, NEW YORK, ASSIGNOR TO THE RAIL JOINT COMPANY, OF NEW YORK, N. Y., A CORPORATION OF NEW YORK

COMPENSATING BUSHING FOR RAIL JOINTS

Application filed April 2, 1929. Serial No. 351,940.

This invention relates to practical improvements in rail joints and has for its object to provide simple, inexpensive efficient means to compensate for the difference in diameter between the bolts and the bolt holes in the rails, particularly of insulated joints, whereby longevity of the joint bars and particularly of the joint insulation may be obtained.

10 In the production of rail joints it is standard practice to provide in the webs of the rails bolt receiving holes considerably larger in diameter than the diameter of the joint bolts in order to allow for expansion and contraction of the rails due to temperature changes. The resulting clearance between the bolts and the sides of the holes allows a gap between the rail ends of usually from one-eighth to one-quarter of an inch in width, 15 or even more, when the rails are moved apart to the furthest limit allowed by the bolts. This gap is necessary, but is recognized as being destructive to both joint bars and rail ends because of the pound produced by wheels 20 jumping thereover. In an insulated joint it is considerably more destructive than in an all-steel joint because an insulating end post at least one quarter of an inch in thickness must be inserted between the ends of 25 the rails, and when the usual expansion allowance is added there results a gap between the rail ends of anywhere from three-eighths to three-quarters of an inch in width and the 30 pound of the wheels across this excessive gap subjects all parts of the joint, and particularly the insulation, to excessive wear. To 35 reduce this gap to a minimum it has been customary to punch the bolt holes in the joint bars so that they will not center with the 40 holes in the rails, i. e., to punch them so that when the bolts are engaged therein they will hold the rails from moving apart to a greater extent than the thickness of the insulated end post. Such a method of placing the bolts 45 offers no resistance, however, to the rail ends moving together and crushing out the insulating end post, and consequently end post renewals heretofore have of necessity been frequent. The problem of gaining longer life 50 for the insulation and also for the other joint

parts is solved according to this invention by punching the bolt holes in the joint bars so that the bolts will center in the rail holes, and by providing bushings to surround the bolts and to substantially fill the spaces between the bolts and the walls of bolt holes in the rails, whereby the bolts may be caused to function to hold the rails against movement both towards and away from one another.

55 The present inventive idea is capable of embodiment in different structural arrangements, certain of which are illustrated in the accompanying drawings. It is to be understood, however, that the structures shown are 60 intended merely as disclosures of the essential features and novel characteristics of the invention in certain preferred forms and that various modifications thereof may be resorted to within the spirit and scope of the invention as defined in the appended claims.

65 In the accompanying drawings, wherein like characters of reference denote corresponding parts in the different views:—

70 Figure 1 is a longitudinal sectional view 75 of a well known form of rail joint having the present improvement, in one practical form embodied therein before flanging.

75 Figure 2 is a transverse section of the joint shown in Fig. 1 after flanging.

80 Figure 3 is a view similar to Fig. 2 showing another embodiment of the invention.

85 Figure 4 is a view similar to Figs. 2 and 3 showing a further modification of the invention, and

90 Figure 5 is a perspective view of the compensating bushing shown in Figs. 1 and 2.

95 Referring to the drawings in detail, it will be observed that the rail joint shown is of conventional design and includes in its organization the rails A, the joint bars B, located at opposite sides of the rails, respectively, which bars may be of any preferred type, and joint bolts C engaged through holes in the joint bars and the rails to maintain the joint parts assembled.

100 Although the present improvements are not restricted to incorporation in insulated joints or in joints of any special or particular construction, it is in insulated joints that

they are possessed of most marked utility and accordingly a well known form of insulated joint has been chosen for purposes of illustrating the invention. This joint is of the well known continuous type employing the usual head and base insulation 10, 11, respectively, between the joint bars and the rails; bolt insulating sleeves 12 between the bolts and the walls of the bolt holes in the joint bar; suitable insulation 13 between the heads and the nuts of the bolts and the outer faces of the joint bars, respectively, and an insulating end post 14 between the ends of the rails.

As previously mentioned it is standard practice under normal conditions to drill the bolt holes in the webs of the rails considerably larger in diameter than the bolts that are to be engaged therein, and to punch the bolt holes in the joint bars so that they will not center with the holes in the rails, whereby the bolts will serve to prevent the rails being moved more than a predetermined distance apart. As is apparent, however, this method of placing the bolts offers no resistance to the rails moving together and crushing the end post 14. Under other conditions it frequently is necessary to employ bolts of smaller than standard diameter for certain joints, for example, in joints where bolts of relatively small diameter are necessitated on account of restricted fishing dimensions of the joint bar sections, which means, of course, maximum permissive movement of the rails relatively to one another. Accordingly, it is proposed by the present invention to punch the holes in the joint bars so that they will center with the holes in the rails and to fill or substantially fill the space between the bolts and the walls of the bolt holes in the rails by suitable means such as bushings 15, whereby any appreciable movement of the rails either towards or away from one another will be prevented.

If the spaces between the bolts and the walls of the bolt holes in the rails are not of too great width single bushings such, for example, as illustrated in Figs. 1, 2 and 5 may be employed to fill or substantially fill them. In fact, single bushings may be employed irrespective of the clearance between the bolts and the walls of the bolt holes in the rails, but in order to provide a flexible and economical stock arrangement of bushings for fitting different diameters of bolts and bolt holes, it may be preferable to provide the bushings in different sizes to be fitted into or telescope with one another, as illustrated for example at 16 in Figs. 3 and 4 of the drawings, whereby, irrespective of the width of the clearance space to be filled or substantially filled, different sizes of bushing used in multiple, that is, fitted into or telescoped with one another, may be employed to eliminate the excessive clearance.

In either event, the bushings may be initially flanged at one end as indicated at 17 in Figs. 2, 3 and 5 of the drawings for engagement with one side of the rail web when they are slipped into the bolt holes, to prevent them from passing through the web, and, if desired, their unflanged ends may be provided with any suitable number of slits 18 or other instrumentality to facilitate flanging over of such ends following installation, which operation may readily be accomplished by the trackman just prior to applying the joint bars and bolts. Furthermore, their surfaces may be smooth to enable them to be slipped endwise into one another, or they may be threaded as illustrated in Fig. 4 so that they may be screwed into one another, in which event it is contemplated that each of them will be provided at one end with a flange 19 so that by inserting one from one side of the rail and another from the other side of the rail they may be drawn tightly into engagement with one another to secure them in the bolt holes.

It is apparent that the use of bushings or fillers as shown and described will effect material economy in rail joints by restricting insulation abrading and crushing movements of the parts of the joints and thereby reducing the frequency of necessary renewals of the various insulation members.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

I claim:—

1. An insulated rail joint construction, including in combination with the rail having a bolt hole therein, the joint bars having bolt holes axially aligned with the bolt hole in the rail, and the joint bolt extending through the aligned bolt holes and of less diameter than the same, of a separate insulating bushing unit substantially filling the interval between the bolt and the wall of the bolt hole in the rail and having holding elements at opposite ends thereof for cooperation with opposite sides of the rail web, respectively, to retain said unit within the hole in the rail.

2. An insulated rail joint construction, including in combination with the rail having a bolt hole therein, the joint bars having bolt holes axially aligned with the bolt hole in the rail, and the joint bolt extending through the aligned bolt holes and of less diameter than the same, and joint insulation including multiple telescoped bushing elements substantially filling the space between the bolt and the wall of the bolt hole in the rail, said bushing elements being formed at their ends for cooperation with one another and with

opposite sides of the rail web to retain said elements in telescoped relation to one another and within the hole in the rail.

3. An insulated rail joint construction, including in combination with the rail having a bolt hole therein, joint bars having bolt holes axially aligned with the bolt hole in the rail, and a joint bolt extending through the aligned bolt holes, of joint insulation including a separate filler bushing substantially filling the space between the bolt and the wall of the hole in the rail, said bushing being flanged at one end and slit at the other.

In testimony whereof I hereunto affix my signature.

EDWARDS F. SCHERMERHORN.
